UNITED STATES PATENT OFFICE.

FRANK W. GAULT, JR., OF OKOLONA, KENTUCKY.

AIR AND GAS MIXER.

1,286,582.

Specification of Letters Patent.

Patented Dec. 3, 1918.

Application filed January 17, 1918. Serial No. 212,195.

To all whom it may concern:

Be it known that I, FRANK W. GAULT, Jr., a citizen of the United States, residing at Okolona, in the county of Jefferson and 5 State of Kentucky, have invented certain new and useful Improvements in Air and Gas Mixers, of which the following is a specification.

This invention relates to a device adapted 10 to mix air and fluid hydrocarbons previous to delivery of same to a burner for consumption.

A suitable mixture of air (oxygen) and 15 gas (hydrocarbon) may be burnt progressively and complete combustion attained in a closed chamber without the admission thereto of atmospheric air.

By so burning air and gas in a closed 20 chamber under a heat absorbing medium a maximum utilization of the B. T. U. in the gas may be obtained.

An object of this invention is the provision of means whereby air and fluid hydrocarbons may be thoroughly mixed and 25 whereby the quantities of the ingredients entering into the mixture may readily be regulated.

With the foregoing and other objects in view, the invention consists of the novel construction and arrangement of parts illustrated in the accompanying drawings, comprising two sheets, which form a part of this specification, wherein is set forth an embodiment of the invention, but it is to be understood that such changes and modifications 35 may be resorted to as come within the scope of the appended claims.

In the drawings, wherein similar reference characters designate like parts in the 40 several views, Figure 1, is a top plan view of an embodiment of the invention: Fig. 2, a rear elevation with connections removed: Fig. 3, an end elevation: Fig. 4, a transverse section on line 4—4 of Fig. 2, with 45 parts omitted; Fig. 5, a section on line 5—5 of Fig. 2, with parts of the induction tube broken away and the tube leading to the burner omitted: Fig. 6, a longitudinal section on line 6—6 of Fig. 3, some parts being omitted to give a clearer understanding 50 of the construction: Fig. 7, a section on line 7—7 of Fig. 6: Fig. 8, a vertical central longitudinal section of a modified form: Fig. 9, a section on line 9—9 of Fig. 8. 55 The embodiment of the invention illustrated herewith comprises a substantially rectangular body, or block —1— provided with a longitudinal mixing chamber —2—, formed by boring, and counter boring from each end the block in such a manner as to 60 leave an internal annular shoulder —3—, against which a foraminous diaphragm may be placed. The ends of this chamber are closed by suitable means such as screw plugs —5—. A centrally positioned opening 6—6—, extended in from the rear of the block to a connection with the mixing chamber is provided with suitable means, such as screw threads —7— whereby an induction nozzle —8— may be adjustably positioned 70 therein, a lock nut —9— serving to secure it in adjusted position. An opening —10— on the opposite side of the block from, and in axial alinement with the openings 6, is provided with suitable means, such as screw 75 threads —11— permitting of the securing therein of a conduit —12— which leads to a burner. Openings —13— positioned respectively on each side of the opening 6 lead from the exterior into the mixing chamber. 80 Suitable means are provided for regulating the admission of air through these openings into the mixing chamber, at atmospheric pressure. As illustrated herewith, said means comprise plates —14— which fit close 85 against the block and are pivotally secured thereto by suitable means as screws —15—. The bodies of these plates are of such size that when in a closed position they completely cover the openings 13. The frictional contact of the plates with the block is such that they will remain in any position to which moved. Extensions —16— serve as 90 handles by means of which the plates may be shifted. The openings 13 are provided with screw threads —17— permitting of the attachment of pipes which may be extended exterior of the apartment in which the mixer is located, for the purpose of procuring air with a larger oxygen content. In such cases 95 the plates 14, would be dispensed with and a valve would be interposed in the continuity of the pipe to control the admission of air. The openings 13 are of the same size as the mixing chamber, so that if desired the plugs 100 5 may be placed in them and the valves 14 placed over the ends of the mixing chamber (Fig. 8). A gas chamber —20— arranged near each end of the block extends transversely therethrough, in a plane parallel 110 with, but spaced from the mixing chamber. The gas chamber communicates with the

mixing chamber by means of passages —21—. Openings —22— through the walls of the gas chamber provide means whereby access may be had to the interior thereof for the purpose of drilling the passages 21, or for reaming them out, if too small. The ends of the gas chambers are provided with suitable means, such as screw threads —23— whereby one end may be closed by suitable closures—such as plugs —24— and for the connection therewith at the other ends of pipes —25—, which by suitable connections, such as unions —27—, and a T —28— may be connected with a gas supply pipe —29—. A conduit —30— attached to the nozzle 8 leads from suitable means (not shown) adapted to supply air under pressure. In the modification shown in Fig. 8, a gas chamber —40— is arranged longitudinally of the block and communicates with the mixing chamber by means of passages —41—. Suitable means are provided for controlling the flow through the passages, such as conically pointed plugs —42—, or needle valves —43— which are positioned in a threaded opening —44—. The ends of the gas chamber 40, are closed by plugs —45—. Gas is supplied to the chamber by means of a valved pipe —46— connected in a threaded opening —47—. The opening —47— and the ends of the gas chamber are adapted to receive either the supply pipe or the plugs, so that the attachment may be made as suits the exigencies of the case. A conduit —31— tapped in an opening —32— through a wall of the mixing chamber leads from a suitable source of supply (not shown) and is provided with suitable means such as a valve —33— whereby liquid hydrocarbons from said source may be admitted in desired quantities to the mixing chamber. The mixer as described is located in proximity to the chamber within which the burner is positioned. In operation, gas is first admitted to the gas chamber, usually from city mains, under normal pressure, of five or six ounces. Air under suitable pressure, which may vary according to conditions connected with the installation, is then admitted into the mixing chamber which it enters with great velocity, creating a partial vacuum therein and drawing in gas. The gas is then lighted at the burner. Free gas in suitable volume is then admitted into the mixing chamber, by manipulating the valves 14. Greater heat may be obtained by introducing a liquid hydrocarbon, such as gasoline into the mixing chamber, through the conduit 31, adding it to the air and gas. Passage of air and gas through a foraminous partition —35— serves to give a more thorough mixture of the gas and air molecules. By means of this improved mixer, air and gas may be delivered to the burner in such proportions and such pressure as to at-

tain complete combustion in a closed chamber.

Having thus described my invention so that anyone skilled in the art pertaining thereto can make and use the same, I claim: 70

1. In a mixer as characterized, a body having a mixing chamber, and having a plurality of openings thereinto, an induction nozzle extending therewith through one of said openings, an eduction tube leading from 75 an opening opposite said nozzle, plugs closing certain of the openings, valves covering the other of the openings, a gas chamber lying in a plane parallel with the mixing chamber and having a passage connecting 80 the two chambers, and having a plurality of openings from the exterior into said gas chamber, a supply pipe fitted in one of said openings and closures fitted in the other of said openings. 85

2. In a gas burner as characterized, a body having a bore extending the full length thereof forming a mixing chamber and having a pair of openings through the walls of the chamber, plugs adapted to close either 90 the end of said bore or said openings and valves adapted to be positioned over those not so closed, an induction nozzle intersected through the wall of the chamber, and an eduction tube leading from the chamber. 95

3. In a gas mixer as characterized, a body having a bore extending the full length thereof forming a mixing chamber and having a pair of openings through the walls of the chamber, plugs adapted to close either 100 the end of said bore or said openings, valves adapted to be positioned over those not so closed, an induction nozzle intersected through the wall of the chamber, an eduction tube leading from the chamber, the body having a second bore extending through same forming a gas chamber, and having a passage connecting the two chambers, plugs closing the ends of the said bore, a supply 105 pipe connected to the gas chamber, the wall of the gas chamber having a perforation opposite said passage and a conically pointed plug in said perforation adapted to control the flow of gas through the passage. 110

4. In a gas mixer as characterized, a body having a bore extending the full length thereof forming a mixing chamber, and having a pair of openings through the walls of the chamber, plugs adapted to close either 115 the end of said bore or the openings, valves adapted to be positioned over those not so closed, an induction nozzle inserted through the wall of the chamber, an eduction tube leading from the chamber, said body having a second bore forming a gas chamber, the body having a passage connecting the two chambers, plugs closing the ends of said 120 second named bore, a supply pipe connected to the gas chamber, the walls of the gas chamber having a perforation opposite said 125 130

- passage, and a valve adapted to control the flow of gas through the passage.
5. In a mixer as characterized, a body having a mixing chamber, and having a plurality of openings into said chamber from the exterior, an eduction nozzle extending into the chamber, an eduction tube leading therefrom, fixed closures for certain of said openings, valves controlling the other of the 10 openings, a gas chamber communicating with the mixing chamber and having a plurality of openings from the exterior; a supply pipe fitted in one of said openings, and closures for the other of said openings.
- 15 6. In a mixer as characterized, a body having a mixing chamber, and having a plu-

rality of openings thereinto; an induction nozzle extending thereinto through one of said openings, an eduction tube leading from an opening opposite said nozzle, plugs closing certain of the openings, valves covering the other of the openings, a gas chamber lying in a plane parallel with the mixing chamber and having a passage connecting the two chambers and having a plurality of 20 openings from the exterior into said gas chamber, a supply pipe fitted in one of said openings, a valve fitted in another of the openings and controlling said passage, and closures fitted in the other of said openings. 25 30
